(57) **CLAIM**

We claim the ornamental design for a coupler for an excavator or the like, as shown and described.

DESCRIPTION

FIG. 1 is a top plan view of a coupler for an excavator or the like showing new design;

FIG. 2 is a front perspective view thereof;

FIG. 3 is a rear elevational view thereof;

FIG. 4 is a front elevational view thereof;

FIG. 5 is a right side elevational view thereof;

FIG. 6 is a left side elevational view thereof; and,

FIG. 7 is a bottom plan view thereof.

The broken line showing of the coupler is included for the purpose of illustrating unclaimed portions of the coupler for an excavator or the like and forms no part of the claimed design.

FIGS. 1 to 7 show a first embodiment of coupler for releasably attaching an accessory to an arm of an excavator. Those features shown in broken lines form no part of the claimed design.
